UNITED STATES PATENT OFFICE

LEON SPINO, OF CLYDE, NEW YORK

DESIGN FOR A SUGAR BOWL

Application filed December 12, 1931. Serial No. 42,049. Term of patent 3½ years.

To all whom it may concern:

Be it known that I, LEON SPINO, a citizen of the United States of America, residing at Clyde, in the county of Wayne and State of New York, have invented a new, original, and ornamental Design for Sugar Bowl, of which the following is a specification, reference being had to the accompanying drawings, forming part thereof.

I claim:

The ornamental design for a sugar bowl as shown.

LEON SPINO.
